(57) **CLAIM**

The ornamental design for a display screen with animated graphical user interface, as shown and described.

DESCRIPTION

FIG. 1 is a front view of a display screen with an animated graphical user interface showing a first image which is part of a sequence showing my new design; FIG. 2 is a second image thereof; and, FIG. 3 is a third image thereof.

The appearance of the animated images sequentially transition between the images shown in FIGS. 1-3. The process or period in which one image transitions to another forms no part of the claimed design. The broken line showing of all text, icons, portions of the graphical user interface, and the display screen are for the purpose of illustrating portions of the article, and form no part of the claimed design.
